UNITED STATES PATENT OFFICE

JAMES E. JONES, OF CHICAGO, ILLINOIS

FLOOR PLATE

Application filed October 6, 1927. Serial No. 224,444.

My invention relates to floor plates and has particular reference to a floor plate having a flat under surface and a tread surface having projections formed thereon in such manner that the tread surface is not irregular and which prevent slippage over the surface of the plate, and which are so proportioned and arranged that the plate is uniform in strength in a transverse direction.

Another and further object of my invention is the provision of a floor plate having projections thereon which form a tread surface which is regular in form and on which the projections are relatively long and narrow, thereby engaging the soles of shoes as they pass over the plate, preventing slippage and at the same time affording a firm, regular surface which is not uncomfortable particularly to the wearers of thin soled shoes.

Another and further object of my invention is the provision of a floor plate having projections formed thereon and integrally therewith in such manner that the floor plate is easily cleaned and does not have a plurality of interrupted surfaces therein which hold the dirt and refuse, and prevent its ready removal from the plate.

Another and further object of my invention is the provision of a floor plate which, because of the arrangement of the projections on the tread surface thereof, is uniform in cross sectional strength throughout any given area in its length, thereby enabling the plate to be rolled to accurate dimensions without the necessity of trimming the edges and also providing a plate having maximum strength with a minimum quantity of metal placed therein, thus resulting both in the saving of labor in the manufacture of the plate and the saving of material.

Another and further object of my invention is a floor plate having a series of projections thereon which are uniform in size and cross-sectional area, and uniformly spaced with relation with each other, and so arranged that there is no weakening of the plate by the displacement of metal to form the projections, and each projection is so formed during the last pass in the rolling operation of the plate that there is a minimum

displacement of the metal to form the projections.

These and other objects of my invention will be more fully and better understood by reference to the accompanying sheet of drawings and in which:—

Figure 1 is a fragmentary elevational view of the tread surface of my improved plate;

Figure 2 is a side elevational view of the plate shown in Figure 1; and

Figure 3 is an end elevational view of the plate illustrated in Figure 1.

Referring now specifically to the drawings, a floor plate is shown having a flat under surface 10 and having an upper surface 11 upon which is formed a plurality of projections designated as a whole as 12, 12, these projections being arranged in rows longitudinally of the plate and also transversely of the plate, with the projections in each row arranged in staggered relation with the projections in each adjacent row, each of these projections 12 being uniform in dimension and in cross-sectional area. Each of the projections is frusto-conical in cross section and in the form as shown, is approximately one-tenth of an inch in height and has a base portion 13 which is approximately $\frac{1}{2}$ of an inch in width, and sloping side portions 14 and 15 respectively, with a flat upper tread surface 16 which is approximately $\frac{3}{2}$ of an inch in width, thereby presenting at the juncture of the surfaces 14 and 16 an edge 17 with a similar edge 18 being provided at the opposite side of the projection 12 at the juncture of the surfaces 15 and 16, these edges 17 and 18 forming the sole engaging portions of the projections and which prevent slippage of the foot as the shoe is brought into contact with the tread surface of the plate as the plate is walked upon in a transverse direction.

The projections 12 have their longitudinal axes parallel with the longitudinal axis of the plate, and in dimension from the center of one projection to the center of the adjacent projection in a longitudinal direction is approximately $2\frac{1}{8}$ inches. Each of the projections have sloping end surfaces 19 and 20 with edges 21 and 22 being formed at the junction of the surfaces 19 and 16 and

100

20 and 16 respectively, thereby forming edges adapted to engage the shoe of the wearer when walking in a direction longitudinally of the plate.

5 It will be noted that the edges 21 and 22 respectively are in substantial alignment with each other, there being a very slight overlap of these edges in the projections to slightly compensate for the small quantity of metal which is moved out of the body of the plate to form each of the projections. A transverse line of fracture in the plate would run in a zig-zag direction around the ends of the ribs because the plate is stronger through the ribs than through the body of the plate. It 10 will also be noted that there are no diagonally extending regularly formed channels in the plate whereby there may be formed in the plate a line of fracture extending in these directions thereby weakening the plate and rendering it liable to crack along these lines in service.

15 The projections measure from the base in a longitudinal direction or approximately $1\frac{5}{8}$ inches in length and from the center line of 20 one row of projections in a longitudinal direction to the center line of the projections on each side, approximately $\frac{3}{4}$ of an inch, the 25 projections being so arranged that the tread surface forms a smooth supporting surface for the shoe as it is brought in contact with the surface and yet affords sufficient friction between the edges of the various projections on the tread surface of the plate and the shoe 30 to prevent slipping of the shoe on the tread surface of the plate.

35 It will be noted from the foregoing description that the arrangement of the projections upon the tread surface by reason of their 40 staggered relation with each other and the slight overlapping of the projections at their 45 ends, affords a plate which is uniform in strength along cross-sectional lines and therefore the plate may be rolled to very exacting dimensions without the additional trimming operations usually employed to bring plates of this character to proper size.

50 While I have described more or less precisely the details of construction, I do not 55 wish to be understood as limiting myself thereto, as I contemplate changes in form and the proportion of parts and the substitution of equivalents as circumstances may suggest or render expedient without departing from the spirit or scope of my invention.

I claim:

60 A floor plate comprising a rolled metal section having a flat under surface and an upper tread surface having a plurality of 65 rows of elongated rectangular flat topped projections thereon, the said projections being in staggered relation in adjacent rows and having sloping sides making angles with the flat tops and forming non-slipping edges at 70 the line of juncture between said sloping sides

75 and the tops of the projections, and having sloping end portions, the said end portions forming a non-slipping edge with the top portion and the juncture of the said end portion with the side portions.

70 Signed at Chicago, Illinois, this 30th day of Sept., 1927.

75 JAMES E. JONES.
